ATTORNEY

UNITED STATES PATENT OFFICE.

WILLIAM J. KRAMB, OF ROCHESTER, NEW YORK.

COLLAR-BUTTON.

1,313,996.

Specification of Letters Patent. Patented Aug. 26, 1919.

Application filed April 23, 1917, Serial No. 163,969. Renewed November 14, 1918. Serial No. 262,603.

To all whom it may concern:

Be it known that I, WILLIAM J. KRAMB, a citizen of the United States, residing at Rochester, in the county of Monroe and 5 State of New York, have invented certain new and useful Improvements in Collar-Buttons, of which the following is a specification.

This invention relates to collar buttons 10 and the principal object of the invention is to provide means for securing the button in the button hole so said button will be retained therein and cannot drop out.

Another object of the invention is to provide means for gripping the shirt adjacent the button hole between two parts of the button so as to firmly hold the button to the shirt.

Another object of the invention is to provide 20 a detachable portion for holding the shirt between itself and another part of the button.

Another object of the invention is to provide a device of this character which is 25 simple and durable in construction, reliable and efficient in operation and one which can be manufactured and placed upon the market at a minimum cost.

The invention also consists in certain 30 other features of construction and in the combination and arrangement of the several parts, to be hereinafter fully described, illustrated in the accompanying drawings and specifically pointed out in the appended 35 claims.

In describing my invention in detail, reference will be had to the accompanying drawings, wherein like characters denote like or corresponding parts throughout the 40 several views, and in which:

Figure 1 is a side elevation of my invention with parts of the top member broken away to show the relative position of the top and bottom members when secured together.

Fig. 2 is a horizontal section through the top member looking down onto the base thereof, and

Fig. 3 is a top plan of the bottom member. 50 In the drawing, 1^x represents the top member of the button made of one piece of material and of substantially the same shape as the collar button now in use. This member is provided with a bottom 11 having an opening 12 therein to receive a head 13 of a

projection 14 of a lower member 2^x, said projection being formed with a groove 15 for a purpose which will hereinafter appear. A spring 17 is positioned in an annular groove 18 which is formed in the bottom 11 60 by inwardly rolling the annular edge of said bottom. The free ends 16 of the spring are bent inwardly of the bottom 11 and in spaced relation to bridge opposite sides of the opening 12 in the bottom of the top 65 member.

When the projection 14 is inserted through the opening 12 in the bottom 11 of the top member, the head 13 of this projection causes the free ends 16 of the spring 17 70 to separate and permit entrance of the head 13 within the hollow top member 1^x. As the head 13 slides farther into the top member, the ends 16 of the spring will follow the contour of the head and will finally rest in the 75 groove 15 in the projection 14 to secure the top and bottom members together. The groove 15 is so positioned on the projection 14 that there is a space between the bottom 11 and the bottom member 2^x when the two 80 members are secured together. This space between the members is of such size as to permit the two members to firmly grip the portion of a shirt surrounding the button hole therethrough.

It will be seen that the button is firmly held in the button-hole of the shirt, so that there is no danger of the same dropping out, and the full length of the button is free to engage the collar and in putting on and 90 taking off the collar there is no danger of pulling the button through the button hole. Further, the button is prevented from moving in the button-hole, thus preventing the collar from slipping up and down on the 95 neck of the wearer.

It is thought from the foregoing that the advantages and novel features of my invention will be readily apparent.

I desire it to be understood that I may 100 make slight changes in the construction and in the combination and arrangement of the several parts, provided that such changes fall within the scope of the appended claims.

I claim as my invention:

1. A collar button comprising a base and a shank, a second member comprising a base and a hollow shank, a disk having a central opening therein secured in said hollow shank, and a spring secured to said disk and 110

having its ends bridge opposite sides of the opening in the disk.

2. A collar button comprising a base and a shank, a second member comprising a hollow base and shank, a disk having its edge rolled inwardly of the hollow base and secured therein, and a ringlike spring positioned in said rolled edge and having its free ends extended in spaced relation to bridge

the opposite sides of the said opening in the disk.

In testimony whereof I affix my signature in presence of two witnesses.

WILLIAM J. KRAMB.

Witnesses:

THOMAS E. BOAS,
JAMES E. GONTREMONT.
